UNITED STATES PATENT OFFICE.

MARY JOHNSTON LAMBRIX, OF DAYTON, OHIO.

SPLASH-BOARD.

1,225,256.

Specification of Letters Patent.

Patented May 8, 1917.

Application filed October 9, 1916. Serial No. 124,576.

To all whom it may concern:

Be it known that I, MARY JOHNSTON LAMBRIX, a citizen of the United States, residing at Dayton, in the county of Montgomery, State of Ohio, have invented certain new and useful Improvements in Splash-Boards; and I do hereby declare the following to be a full, clear, and exact description of the invention, such as will enable others skilled in the art to which it appertains to make and use the same.

This invention relates to a shield or protector for preventing the splashing of water from a dish-pan or like receptacle and the consequent soiling of the clothes of the person at work.

An object of the present invention resides in the provision of a protector of the above character which may be manufactured from a single blank of material at a relatively low cost and which is capable of general application.

With the above and other objects of similar nature in view the invention consists in the construction, combination and arrangement of parts set forth in and falling within the scope of the appended claim.

In the drawing:

Figure 1 is a perspective view of the improved protector, and

Fig. 2 is a vertical section therethrough illustrating its manner of employment in connection with a dish-pan.

Referring now more particularly to the accompanying drawing the protector is designated generally at 5 and is preferably constructed or formed from a single blank of material such as tin, aluminum, fiber or other suitable composition.

Specifically the protector comprises a

body member 6 constituting what may be termed the apron of the device said body when in use being disposed in a substantially upright position adjacent the dish-pan and receiving therefrom the splash resulting from the washing operation.

This body 6 has its upper and side marginal edges directed at an angle therefrom, as clearly shown, to provide a suitable flange 7 arranged to deflect and prevent the splashed water from passing over said edges.

The bottom edge of the body 6 is reduced or constricted as indicated at 8 and has formed integrally therewith a substantially right angular extension 9 adapted to be engaged between the bottom of the dish-pan 10 and its support whereby to securely hold the protector in position for use as illustrated in Fig. 2.

The operation of the protector is obvious and is thought to need no detailed explanation, while when not in use it may be conveniently suspended from a nail or other similar support through the medium of an opening 11 found in the head 6.

What I claim is:

A protector for dish-pans formed from a single blank of material and comprising a body member having a portion of its margin directed at an angle to the body member to provide a flange, and an angular extension at one edge of the body adapted to be engaged beneath a dish-pan and thereby support the protector in position for use.

In testimony whereof, I affix my signature, in the presence of two witnesses.

MARY JOHNSTON LAMBRIX.
